UNITED STATES PATENT OFFICE.

ASA W. CHAMBERLIN, OF STRATFORD, IOWA.

WIND-WHEEL.

SPECIFICATION forming part of Letters Patent No. 426,241, dated April 22, 1890.

Application filed May 22, 1889. Serial No. 311,701. (No model.)

To all whom it may concern:

Be it known that I, ASA W. CHAMBERLIN, of Stratford, in the county of Hamilton and State of Iowa, have invented a new and useful Improvement in Wind-Wheels, of which the following is a specification.

My invention consists in a new and improved wind-wheel, which will be hereinafter fully described and claimed.

Referring to the accompanying drawings, Figure 1 is a side view of my new and improved wind-wheel. Fig. 2 is a top plan view of the same. Fig. 3 is a detail view of one of the fans. Fig. 4 is a detail view illustrating one of the inner fan-stops, and Figs. 5 and 6 are detail views hereinafter referred to.

The same numerals of reference indicate corresponding parts in all the figures.

Referring to the several parts by their designating-numerals, 1 indicates the vertical shaft, which is revolved by the wind-wheel, being supported in suitable bearings in a frame 2. The upper end of this shaft has the arms 3 projecting at right angles to it, and on these arms are mounted the fans 4. These fans are arranged in vertical planes, half of each fan being above and half below its arm 3. Each fan consists of an upper and lower half connected at their rear edge and secured together by a rod 5, leaving an open space between the halves of the fan, so that it can turn completely around in its bearings on the wheel-arm, as hereinafter set forth. The fans are secured on each arm parallel to each other on the same side of the arm by bearing-plates 6, stops 7 on the rods 5 preventing the upper half of the fan from bearing on the upper part of the arm.

When the fans are "closed," the free front edge of each fan bears against rearward projections 8 of the fan in front of it, these rear projections of the fans serving to hold the fans closed when the wind is blowing against them. The fans are all thus held or braced, except the innermost fan on each arm, which is held shut against a hinged stop 9, consisting of a rod 10, having parallel stop-plates 11 at each end. This rod 10 is supported in a bearing-plate 12 at the rear of the arm 3, as shown, and a projection 13 on the rod holds the upper stop-plate 11 up clear of the arm. When the stop 9 is turned so that the outer

edge of the innermost fan 4 rests against the free ends of the stop-plates 11, the said fan is held or supported in its closed position 55 with the wind blowing against it, and the outer fans rest with their free outer edges against the stops 8, which project, as shown, from the rear of each fan.

It will be seen by reference to Fig. 2, in 60 which the direction of the wind is indicated by the small arrows, that the air pressing on the fans that are to the left-hand side of the central horizontal line xx , looking in the direction indicated by the small arrows, will 65 keep the said fans closed and revolve the wheel in the direction indicated by the large arrows in Fig. 2, while, as soon as the arms pass down below the line xx , the fans all open simultaneously under the pressure of 70 the wind and hang with their edge to the wind, as shown in the right-hand half of Fig. 2, looking in the direction of the small arrows, and when they reach and rise above the line xx they are closed or locked against each 75 other ready to receive the pressure of the wind; but if the hinged stop 9 is drawn or turned toward the center of the wheel, so that it will not catch the free edge of the innermost fan, all the fans on that arm will turn 80 in their bearings and hang edge to the wind, as will be readily understood, so that no pressure will be exerted by the wind on that arm of the wheel.

For automatically regulating the speed the 85 hinged stop 9 of each arm has pivoted to it at the points 13^a one end of a rod 14, the other end of which is pivotally connected to the outer part of a disk 15, which is centrally pivoted on a bracket 16, as shown, and from 90 the lower part of each disk 15 is suspended a governor-ball 17. It will be seen that as the shaft 1 is revolved by the wheel the balls 17 of each arm will swing out and up, turning the plates or disks 15 with them, and when 95 the speed reaches a certain height the governor-balls will rise sufficiently high to turn the disks 15, so that the connecting-rods 14 will draw the hinged stops 9 toward the center of the wind-wheel clear of the inner fans 4, 100 when the fans will turn their edges to the wind and the wheel will slow down, as no pressure can then be exerted by the wind. As the speed falls, the governor-balls will fall

until the stops 9 again engage the inner fans, when the fans will again be held shut for the wind to exert its pressure against them.

To stop the wheel or mill entirely, a tube 5 18 is mounted loosely on the shaft 1, being formed with a slot 19, and a pin 20 in the shaft fits in this slot, so that the tube is held from turning around on the shaft, but can slide up and down thereon. Each disk 15 is 10 pivotally connected to the upper end of the tube 18 by a rod 21, the pin 22 at the upper end of each rod fitting in a curved slot 23 in that disk 15. The lower end of the tube 18 is formed with a flange 23^a, which fits and 15 turns in a collar 24 of a plate 25, the plate remaining stationary while the flanged end of the tube revolves in the collar. One end of the plate 25 is hinged to a bearing 26, while to the other end is secured a rod or cord 27. 20 It will be seen that when the rod 27 is pulled down the plate 25 will draw down the tube 18, which, through the rods 21, will turn the disks 15, so as to turn the hinged stops 9 clear of the inner fans, when the fans will 25 turn their edges to the wind, and the wheel will be thus stopped. The curved slots 23 in the disks 15 permit of the disks being turned by the governor-balls 17 without moving the tube 18. It will be seen that the nearer the 30 point of attachment of the governor-ball is to the end of the rod 14 on its disk 15 the higher the governor-ball will have to swing to draw the stop 9 free of the innermost fan. Therefore by putting the governor-balls of two op- 35 posite arms at the same distance from the rods 14 on their disks and placing the governor-balls of two opposite arms at points farther down on their disks, requiring a higher rate of speed to open their fans, the wheel 40 will be so gaged that it cannot run above a certain speed even if the work be light, as will be readily understood. The power can be conveyed from the vertical revolving shaft 1 either by a belt or gear-wheels in the usual 45 manner. The outer ends of the fan-arms are connected by brace-rods 28.

My new and improved wind-wheel is simple and strong in construction and exceed-

ingly efficient in its operation. It dispenses with the usual vane, and the pressure of the wind is direct instead of glancing.

Having thus described my invention, what I claim, and desire to secure by Letters Patent, is—

1. In a wind-wheel, the combination, with 55 a fan-arm, of the fans consisting of the upper and lower halves 4 4, having the rear projections 8, and connected by the edge rod 5, having the stop, and the stop hinged on the arm and consisting of the rod 10, having the end 60 plates 11 11 and the projection 13, substantially as set forth.

2. In a wind-wheel, the combination, with 65 the vertical shaft and the fan-arms, of the fans formed with the upper and lower blades 4 4 and having the rear projections 8, the stops 9, having the upper and lower plates 11 and hinged on the arms, the disks 15, centrally pivoted on the brackets 16, the rods 14, pivotally connecting the stops 9 and the 70 disks 15, and the governor-balls 17, attached to the disks, substantially as set forth.

3. In a wind-wheel, the combination, with 75 the vertical shaft and the fan-arms, of the fans 4 4 5, having the rear projections 8, the stops 9, hinged on the arms, the disks 15, centrally pivoted on the brackets 16 and having the curved slots 23, the governor-balls 17, the slotted movable sleeve 18, and the stop-pin 20, and the connecting-rods 14 and 21, sub- 80 stantially as set forth.

4. In a wind-wheel, the combination, with 85 the vertical shaft and the fan-arms, of the fans 4 4 5, having the rear projections 8, the stops 9, hinged on the arms, the disks 15, centrally pivoted on the brackets 16, the slotted movable sleeve 18, having the flange 23^a at its lower end, the connecting-rods 14 and 21, the hinged plate 25, formed with the collar 24, and the rod 27, connected to the plate 25, 90 substantially as set forth.

ASA W. CHAMBERLIN.
